HAND OPERATED LOCK

John Holtzman, New York, N. Y.

Original application March 12, 1925, Serial No. 14,980. Divided and this application December 24, 1930, Serial No. 504,516½

14 Claims. (Cl. 70—74)

My invention relates to hand operated locks, of a type suitable for use upon doors and the like, my improved lock having a number of bolts movable relatively to each other, and coacting with each other and with other parts, in order to increase the security and efficiency of the lock.

This application is a division of my pending application for patent upon door locks, Serial No. 14,980, filed March 12, 1925.

10 Reference is made to the accompanying drawings forming a part of this specification and in which like letters indicate like parts throughout all of the figures.

Figure 1 is a longitudinal section through my improved lock, and is taken upon the line 1—1 of Figure 2, looking in the direction indicated by the arrows.

Figure 2 is a section taken on the line 2—2 of Figure 1, looking in the direction indicated by the arrows.

Figure 3 is a section on the line 3—3 of Figure 2, looking in the direction indicated by the arrows.

Figure 4 is a plan view of a knob forming a part of my improved lock.

25 Figure 5 is a perspective of the lock casing.

Figure 6 is a plan view of the key used in connection with my lock.

Figure 7 is an edge elevation of the key.

A casing 90 is provided with a front plate 91, having side and end walls 92, and also inwardly extending walls 93. The casing also has a flange 94, located upon its under side and partially covering the bottom, toward the front.

A plate 95 extends over the inner side of the flange 94, and is attached by screws to bosses in the casing, so as to form a complete bottom wall.

A knob 96 is revolubly mounted in the front plate 91, and is provided with a stem 97, the latter having an axial bore 98. Rigidly mounted on the stem is a double ended lever, one end 99 of same being disposed in the plane of its hub and the other end 100 offset, for a purpose hereinafter described.

An inner casing 101, shown more particularly in Figure 5, having side walls 102 and 103 and edge walls 104 is slidably mounted within the casing 90, the edge walls 104 being in contact with the side walls 92 of the casing. One of the side walls, 103, is in contact with the bottom plate 95, and the other side wall 102 being guided by the cover plate 91.

The side walls 102 and 103 are provided respectively with recesses extending from their rear ends, as shown at 105, and leading from these recesses are a pair of shorter recesses 106 and 107,

extending transversely, the entrances to these last mentioned recesses being beveled as shown in Figure 5.

Referring to Figure 1, it will be noted that the arm 99 is adapted to enter the recess 106 whenever the knob 96 is rotated, but the offset arm 100 does not enter the recess just mentioned. The arm 100, being in a plane different from that of the side wall 102, simply moves idly along the surface of this side wall.

Three separate bolts are used in my lock, namely, a center bolt 108 and a pair of side bolts 109 and 110. The center bolt 108 is provided with a centrally disposed elongated slot 111, through which extends a pin 112, fixed in the side plates 70 102 and 103 to guide and limit the bolt in its movement in its relation to the inner casing.

A pair of arms 113 and 114, spaced apart, extend rearwardly from the bolt. The arm 113 has a raised portion 115, and the arm 114, which is somewhat wider than the arm 113, is provided with a recess 116, so located as to receive the offset arm 100, by the regular movements of which the bolt may be operated.

A keeper 117, having a box-like form, is secured upon the jamb of the door by screws extending through the flange 118 of the keeper. The keeper is open on the side next the lock, except for inturned flanges 119 at its ends. These flanges, when the door is closed, are located adjacent the flanges 93 of the lock casing.

The bolts 109 and 110 are of the same shape and construction but are reversed in position. These bolts have heads which are normally held in contact with the head of the center bolt 108 90 by means of compression springs 120, set into openings in the outer edges of the side bolts, these springs abutting the inner walls 104 of the movable casing 101.

The side bolts 109 and 110 have recesses 121 in 95 their outer edges, so disposed as to clear the flanges 93 and 119. The heads of the side bolts extend like hooks over the recesses 121 and the side bolts can only be released by retracting the center bolt 108 so that its head is withdrawn 100 sufficiently to extend into the spaces of the side bolts, beyond the shoulders 122, from which the heads of the side bolts extend.

The side bolts are provided with stem portions of reduced diameter and extending rearwardly. 105 These stem portions are closely adjacent the inner edge walls 104 of the casing, and terminate in bosses 123, the inner surfaces of which make sliding contact with the arms 113 and 114 respectively, of the center bolt.

The bosses 123 are bored to receive sleeves 124. These sleeves extend through openings 125 in the sides of the inner casing. Carried in these sleeves 124 are spherical members 126, pressed outwardly 5 into depressions 127 and 128 formed in spaced relation within the cover plate 91, by means of compression springs 129 held in the sleeves and backed by screws 130.

In order to operate the bolts, the knob 96 is 10 rotated by hand to the extent of a full turn, one-half of this turn serving to retract the center bolt. This is done by means of the lever 100, extending into the recess 116. The other half of the turn of the knob causes the lever 99 to 15 extend into the recess 106, thus moving the inner casing 101 and the side bolts 109 and 110, as a unit, rearwardly.

The inner casing and the two side bolts are held in their respective positions into which they 20 are thus moved, this being done by spherical members 126, extending into either the front depression or the rear depressions in the casing cover.

The lock is provided with means whereby it 25 may be operated by means of a key. The mechanism for this purpose is located upon the opposite side of the door from the parts just mentioned, and consists of a cylinder lock, generally designated by the numeral 135. This cylinder lock 30 is provided with a flanged base 136, adjustably held in position by bolts extending through the plate 137 set in the door.

The cylinder lock, which may be of any approved type, is provided with a flat stem 138 35 extending into the opening 98 of the knob 96 and into the lock casing, through a bushing 139 which is revolvably mounted in the bottom plate 95 of the lock casing.

Rigidly mounted upon the extending end portion of the bushing 139 is a lever having arms 40 140 and 141, the last mentioned arm being offset inwardly to clear the inner casing recess 107, the first mentioned arm being arranged to extend into the recess 116 of the center bolt, and thus 45 being adapted to operate the lock by the insertion and turning of a key, in substantially the same manner as by rotation of the knob 96.

A flanged disk 142, disposed at the outer end 50 of the cylinder 135, is screw-threaded on its outer surface and engages a dial 143. This dial is provided with an opening 144, so positioned as to register with a key passage 145, for a cylinder lock key 146 of the usual flat type.

The dial is normally held in proper adjustment 55 to either cause the opening 144 to register with the key opening 145, or else remain out of registry to prevent the entrance of a key. For the purpose of thus holding the dial I provide a screw 147, having a square head extending into an opening 148 60 in the dial, the screw being threaded and fitted into the flanged disk 142, and operated by aid of a wrench 149, formed on the stem of the key 146.

Except as above noted, my improved lock is in structure and action like other locks heretofore 65 known.

I do not limit myself to the precise mechanism shown, as variations may be made therein without departing from my invention, the scope of which is commensurate with my claims.

Having thus described my invention, what I 70 claim as new and desire to secure by Letters Patent is as follows:

1. A door lock comprising a casing body and a keeper, an inner casing slidably mounted within 75 said casing body, a pair of bolts pivoted to said

inner casing, a single bolt located between the pair of bolts and movable independently thereof, a lever revolvably mounted within said casing body and provided with two arms, one of said arms being mounted to engage said center bolt and to move the same, the other of said arms being mounted to engage the inner casing and shift the position thereof, a knob mounted upon one side of said casing body for manually rotating said lever, a second lever also mounted to move the casing and center bolt, and key operated mechanism mounted upon the side of said casing body opposite said knob, for the purpose of rotating said second mentioned lever independently of said knob.

2. A lock including a casing having a cover, a frame disposed within said casing and consisting of a substantially constant gauge metal, a bolt for said lock, said frame having means for guiding and limiting the movement of said bolt in relation to said frame to its locking and unlocking positions, and said inner frame serving as a rest for the cover plate to close the lock casing, and means for moving said bolt.

3. A lock including a casing having a cover, a frame disposed within said casing and consisting of a substantially constant gauge metal, a bolt for said lock, said frame having means for guiding and limiting the movement of said bolt in relation to said frame to its locking and unlock- 100 105 positions, and said frame serving as a rest for the cover plate to close the lock casing, and means for moving said bolt, said means for guiding and limiting the movement of the bolt comprising a pin transversely supported upon said frame and 110 extending through a slot in said bolt.

4. A lock including a casing having a cover, a frame disposed within said casing and consisting of a substantially constant gauge metal, a bolt for said lock, said frame having means for guid- 115 120 125 ing and limiting the movement of said bolt in relation to said frame to its locking and unlocking positions, and said inner frame serving as a rest for the cover plate to close the lock casing, and means for moving said bolt, a boss extending outwardly from said casing through an opening in said inner frame for retaining said cover plate.

5. A door lock comprising a casing body, an inner casing slidably mounted within said casing body, a pair of bolts pivoted to said inner casing, 125 130 135 a bolt located between the pair of bolts and movable independently thereof, said latter bolt being adapted to hold said pair of bolts in locked position with relation to a keeper, a lever revolvably mounted within said casing body and provided with a plurality of arms, one of said arms being arranged to engage said center bolt and to move the same, the other of said arms being arranged to engage said inner casing and to shift the same within said casing body, and means for operating said lever.

6. A door lock comprising a casing body, an inner casing slidably mounted within said casing body, a pair of bolts pivoted to said inner casing, 140 145 150 a bolt located between the pair of bolts and movable independently thereof, said latter bolt being adapted to hold said pair of bolts in locked position with relation to a keeper, a lever revolvably mounted within said casing body and provided with a plurality of arms, one of said arms being arranged to engage said center bolt and to move the same, the other of said arms being arranged to engage said inner casing and to shift the same within said casing body, and means for operating said lever, said lever arms arranged to slide 150

- said center bolt and said inner casing in sequence.
7. In a lock, the combination with a casing, a hook shaped bolt pivotally mounted in the casing, a mechanism to operate the bolt including a movable member arranged to be reciprocated in the casing, a lever rotatably mounted in the front wall of said casing to actuate said reciprocating member, a pin secured in the casing, said reciprocating member having a slot in which said pin engages to guide the reciprocating member, said reciprocating member operating to rock said hook shaped bolt on its pivot for interlocking engagement with a keeper, a cover detachably secured to the rear face of the casing to cover the mechanism and to maintain said mechanism against displacement laterally of said casing, a knob connected to said lever and arranged in the front of the front face of the casing to operate the lock.
- 10 8. In a lock, the combination of a lock casing, an inner casing slidably mounted within said lock casing and movable relatively thereto, a pair of rockingly mounted bolts each having a pivot in said inner casing, a third bolt intermediate said first bolts and movable longitudinally in said inner casing, and adapted to be projected into a keeper, means within said inner casing for guiding said third bolt, a lever mounted in the wall of the lock casing and adapted to move the inner casing with the bolts confined therein as a unit, and key operated means to turn said lever to actuate the lock.
- 15 9. In a lock, the combination of a lock casing, an inner casing slidably mounted within said lock casing and movable relatively thereto, a pair of rockingly mounted bolts each having a pivot in said inner casing, a third bolt longitudinally movable intermediate said first mentioned bolts in said inner casing and adapted to be projected into a keeper, means within said inner casing for guiding said third bolt, a lever mounted in the wall of the lock casing and adapted to move the inner casing with the bolts confined therein as a unit, and key operated means to turn said lever.
- 20 10. In a lock, the combination of a lock casing, a second casing movable relative to and disposed within the lock casing, two bolts pivotally mounted in said second casing, spring means carried by said second casing for moving the two bolts toward each other, a lever rotatably mounted in the lock casing for moving said second casing, a third bolt mounted in said inner casing adapted to be projected into a keeper and to move the two bolts out of the casing and turn them on their pivots into locked position with the keeper, and manual means to actuate said lever.
- 25 11. In a lock, the combination of a lock casing, a keeper, an inner casing slidably mounted within said lock casing, a pair of bolts pivotally mounted in the inner casing, springs mounted in the casing for yieldingly moving the outer ends of the bolts into position to enter the keeper, a third bolt movable in the inner casing intermediate said two first mentioned bolts and adapted to be projected into the keeper, a lever rotatably mounted in the lock casing, said lever adapted to move
- first the inner casing with the pivotally mounted bolts located therein, thereby moving said bolts into the keeper and to then move said third bolt to cause it to enter the keeper, thereby swinging the two bolts on their pivots, against the action of the springs, to their locking position, a cover plate detachably secured to the lock casing for maintaining said bolts in operative position, and manual means to actuate said lever to operate the lock.
- 30 12. In a lock, the combination of a casing, two bolts pivoted thereto, a third bolt slidably mounted intermediate said two bolts for moving the latter longitudinally, means mounted in the casing for guiding said third bolt in a straight line path, key actuated means for moving said third bolt from the casing into a keeper and causing said two first mentioned bolts to be turned on their pivots, a stationary lock casing in which said first casing is mounted for longitudinal movement, and a lever rotatably mounted in the lock casing for moving said first casing with the bolts confined therein as a unit, and manually operated means to turn said lever.
- 35 13. In a lock mechanism the combination of a casing, a main bolt movable within the casing and adapted to be projected into a keeper, a pair of hook-shaped supplementary bolts mounted within said casing, said supplementary bolts adapted to move up and down and being actuated by the movement of said main bolt for interlocking engagement with a keeper, a lever rotatably mounted in the front wall of the casing to actuate the main bolt, a cover plate detachably secured to the lock casing for keeping and guiding the mechanism in its movement, a flange integral with the casing and arranged to overlap the cover plate to prevent said plate from lateral displacement when said plate is resting on said mechanism, means for fastening said plate to the lock casing, a second lever rotatably mounted in the cover plate, spring means associated with said mechanism for keeping said bolts in operative position, and key operated means to rotate said last mentioned lever to operate the lock.
- 40 14. In a locking mechanism the combination of a casing, a main bolt movably mounted within the casing and adapted to be projected into a keeper, a pair of hook shaped supplementary bolts movably mounted within said casing and being actuated by the movement of said main bolt, a lever rotatably mounted in the front wall of the casing for moving the main bolt, a cover plate detachably secured to the lock casing for guiding said bolts in their movement into locking and unlocking positions, a flange integral with the casing overlapping the cover and securing said cover against lateral displacement, said mechanism providing a rest for said cover plate when said plate is fastened to the lock casing, a second lever rotatably mounted in the cover plate to operate said mechanism from the outdoor side of the casing, and key actuated means to turn said latter lever.

JOHN HOLTZMAN. 140
